(57) **CLAIM**

We claim the ornamental design for a portable computer, as shown and described.

DESCRIPTION

FIG. 1 is a front perspective view of a portable computer of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof;

FIG. 8 is an enlarged view of selected portion 8 in FIG. 2; and,

FIG. 9 is another enlarged view thereof, showing portion 8 of FIG. 8 in an opened state.

The broken lines in the drawings represent portions of the portable computer and form no part of the claimed design. The other broken lines in FIGS. 8 and 9 represent an enlarged view only and form no part of the claimed design.

1 Claim, 9 Drawing Sheets
